Inventor.

UNITED STATES PATENT OFFICE.

CHARLES LA DOW, OF ALBANY, NEW YORK.

CULTIVATOR.

SPECIFICATION forming part of Letters Patent No. 251,252, dated December 20, 1881.
Application filed August 6, 1881. (Model.)

To all whom it may concern:

Be it known that I, CHARLES LA DOW, a citizen of the United States, residing in the city and county of Albany, and State of New York, have invented a new and useful Improvement 5 in Cultivators; and I do hereby declare the following to be a full, clear, and exact description of the same, reference being had to the drawings and letters of reference thereon.

10 This invention relates to an improved method of attaching independent teeth to the frame of the machine by which a uniform cutting pitch may be maintained and lateral motion of the teeth prevented, and to flexible locking devices 15 for enforcing their cut, and to the manner of regulating their penetration, and for carrying them when not in use, and for changing their pitch in relation to the ground.

Figure 1 shows a top view of my invention. 20 Figs. 2 shows a side view of the locking arms or links and various positions of the teeth. Fig. 3 is a sectional view, illustrating the manner of attaching the locking arms or links to the teeth by means of adjustable clamps. Fig. 4 25 is a rear view of the clamps and a section of a tooth.

The principle upon which this improvement is based is that of opposing levers placed preferably in parallel planes, held at proper distances apart by connecting links or blocks, and arranged in such manner that the rearward strain on one lever will be counteracted by the other, which exerts a flexible locking tendency 30 upon the independent teeth in all positions of their movements, allowing them to rise and fall to suit the inequalities of the surface, and at the same time enforcing uniform cutting action 35 on all the teeth, some of which may be trailing in a furrow while the adjacent ones may be working on a ridge. The links and parallel levers also brace the teeth against lateral strain and hold them at uniform working pitch during upward and downward movements. Each 40 tooth may thus independently conform to the inequalities of the surface at all times, the opposing levers enforcing the depth of cut, and the runner ends of the teeth preventing too deep penetration, and at the same time acting as stops to prevent overturning sods while the 45 points of the teeth are cutting through them.

In the drawings, A represents the pole; B, the cross-bar or frame; CC, the wheels; E and E', the parallel locking and bracing arms; D and D', the adjustable clamp-links for hinging the teeth 1, 2, and 3 to the parallel arms, and K the brackets for hinging said arms to the frame. The clamps D and D' clasp the teeth, and are held in any desired position thereon by bolts O O. These clamps are made in two parts, one of which, D, is provided with lugs d d to embrace the part D' in order to retain it securely. The clamps regulate the pitch of the cutting end of the teeth, and consequently their inclination to draw down into the earth, which tendency is aided by the locking parallel arms E and E' when rearward strain is applied to the teeth. The desired pitch having been ascertained, the points of the teeth enter the earth until their runner ends bear upon the surface, thus gaging the penetration of said points.

The lever H and bar G (which may be hinged at any convenient point) may be used to elevate the teeth or depress them in order to make them enter very hard ground.

R is a ratchet for holding the lever and teeth in any desired position.

The arms E and E' are provided with feet e e, said feet serving as hinges in the brackets k. a a are hinges at the teeth. The arms E and E' brace the teeth against lateral motion, but allow them free vertical movement in either direction, and said arms cause the teeth to maintain a uniform cutting position when said teeth are working up and down. The runner ends of the teeth press upon the earth and hold sods from overturning while the points of the teeth are cutting through them.

The arms of the bar G may be pierced with holes, and the lower ends of the lever H may be pierced with a slot, s, for moving said bar 9 nearer to or farther from its fulcrum, and thus increase or lessen the range of movement of the arms E and E'. The arms E and E' are attached one to the inside and the other to the outside of the teeth, in order to the better withstand the rocking strain against the teeth, in which position arm E' counteracts the draft and arm E the forward thrust.

It will be observed that the length of the runner ends of the teeth may be regulated by means

the adjusting-clamps to vary the depth of t as well as the inclination or pitch of the teeth.

It will also be observed that the teeth may be raised, carried, or lowered, and, if desired, led down to their work by the lever H and lever G.

It will also be observed that the teeth are independently hinged to the cross-bar by brackets and bracing-arms, which brace and hold the teeth against lateral play, but which allow them free motion up and down.

Runners may be used on the cross-bar instead of wheels, and as many teeth and links may be used in a machine as desired, and they may all be arranged in one gang or in several, may be mounted on arms of equal or unequal lengths, and either rigid or spring teeth may be employed without altering the principles of my invention, which contemplates hinging teeth independently to independent parallel or locking arms, which enforce the cut of the teeth during all changes of position, and brace them against lateral strains, and which cause the teeth to maintain a uniform cutting position, whether raising or lowering. Heretofore the spring-teeth of harrows have been attached to the harrow-frame by placing the end of the teeth on a seat formed on a sider and clamping it thereon by means of a cross-bar and binding-nuts. Spring-teeth have been formed in the arc of a circle and fixed the harrow-frame in such manner that the cut ends of the teeth serve as gages to limit the depth of harrowing; but in these prior arrangements the spring-teeth have not been adapted to freely rise and fall in vertical planes,

and therefore they are essentially different from my invention.

Having described my invention, I claim—

1. In a cultivator, the combination of the pole, cross-bar, wheels supporting the same, teeth independently hinged thereto, parallel arms or links arranged to brace the teeth against lateral motion, and hinges for connecting said links directly to the cross-bar and teeth. 45

2. In a cultivator, the combination of the pole, cross-bar, wheels, teeth, parallel locking and bracing links, hinges for the same, a bar for raising the teeth, and a lever for controlling the position of the bar. 50

3. In a cultivator, the combination of the draft-frame, teeth independently hinged thereto, parallel arms for locking each tooth independently against rearward strains, and clamps for adjusting the pitch of the teeth. 55

4. In a cultivator, the combination of a tooth free to rise and fall vertically and devices arranged to hold one end of the tooth in position to gage the penetration of the other end. 60

5. In a cultivator, the combination of a tooth free to rise and fall vertically and devices arranged to hold one end of the tooth in position to depress the material acted on by the other end of said tooth. 65

6. In a cultivator, the combination of pole A, frame B, wheels C C, independent teeth 1, 2, and 3, laterally-bracing arms E and E', and links D and K, as and for the purpose set forth. 70

CHARLES LA DOW.
